United States Patent Office

Des. 217,883

Patented June 23, 1970

217,883

DECORATIVE LIGHT UNIT

James R. Stober, 435 SE. 28th Ave.,
Portland, Oreg. 97214

Filed Apr. 14, 1969, Ser. No. 16,720

Term of patent 3½ years

Int. Cl. D26—02

U.S. Cl. D48—20

FIG. 1

FIG. 2

FIG. 3

FIG. 1 is a top plan view of a decorative light unit, in accordance with my new design;

FIG. 2 is a side elevation thereof; and

FIG. 3 is a bottom plan view thereof.

I claim:

The ornamental design for a decorative light unit, as shown.
